UNITED STATES PATENT OFFICE.

SERGE OULIANINE, OF SYDENHAM, LONDON, ENGLAND.

SIGNALING APPARATUS.

1,377,521.

Specification of Letters Patent. Patented May 10, 1921.

Application filed July 20, 1920. Serial No. 397,741.

To all whom it may concern:

Be it known that I, SERGE OULIANINE, a citizen of Russia, residing in Sydenham, London, England, have invented certain new and useful Improvements in Signaling Apparatus, of which the following is a specification.

The present invention relates to signaling apparatus employing signal-impulses each consisting of a number of vibrations whose frequency is predetermined. The object of this invention is to provide means whereby, out of a number of impulses of different periodicities, those which are of the predetermined periodicity are selected and are rendered audible. Hereinafter, a device employed to select impulses of a predetermined periodicity from a mixture or number of impulses of differing periodicities, is referred to as a "tone-filter."

Numerous constructions of apparatus have heretofore been proposed to operate as tone-filters, that is to say devices to select operatively impulses of a predetermined periodicity from a mixture of impulses of different periodicities. Such devices have comprised a tunable resonator, such as a stretched string, tuned to the predetermined periodicity referred to, and a vibratory member capable of responding to impulses of heterogeneous periodicities; electro-magnetic means have in some cases been employed to provide the connecting link whereby vibrations from the vibratory member have been imparted to the resonator. In other cases a rigid mechanical connection has been employed as the said link. It has also been proposed, in a transmitter for submarine sound signals, to connect a submerged part of a vessel, such as the wall of a ship, to a tuning fork by means of a spring; both the said vessel and the tuning fork being rigidly connected to the said spring.

In order to render the vibrations more readily discernible it has been proposed to connect a microphone operatively with the resonator and to connect electrically a telephone receiver with the microphone so that the latter shall set up sounds in the telephone corresponding with the vibrations of the resonator.

The present invention relates to the tone-filters of the type in which a tunable resonator is so connected to a receiver or transmitter having a vibratory member capa-

ble of responding to impulses of heterogeneous periodicities that the vibrations of the said member tend to be communicated to the resonator.

The present invention provides a tone-filter of the type defined characterized by the inclusion in the one instrument of a tunable resonator and a resilient member to constitute the link whereby the transmission of vibrations between the receiver or transmitter and the tunable resonator is effected.

When the resonator is an audible one a microphone may be operatively connected with a telephone receiver and mounted either upon a base carrying the resonator or upon the said vibratory member of the receiver so that the signals may be magnified or their transmission to some distance from the apparatus facilitated.

The relative situation between the point of connection of the resonator to the said vibratory member and the nodes in the resonator may be adjustable for the purpose of preventing the said point being at a node.

The accompanying drawings illustrate three alternative constructions, by way of example, and in these drawings—

Figure 1 is a plan of a single form of apparatus embodying this invention;

Fig. 2 is a section on the line 2—2 of Fig. 1;

Fig. 3 is a view similar to Fig. 2 of an alternative construction;

Fig. 4 is a transverse section on the line 4—4 of Fig. 3, and

Fig. 5 is a perspective view of a third construction.

In the construction shown in Figs. 1 and 2, an electro-magnet A is provided, energized from a source which will impart to the electro-magnet current-impulses of diverse periodicities depending upon the signals picked up. The electro-magnet is provided with a resilient tongue B as armature, and a small bent plate-spring C is attached to the armature with its plane arranged at right-angles to the length of the armature. The magnet is secured to a base D which constitutes a sounding-board upon which is a stretched string E, which may be of metal, and which is provided with means at F, whereby the tension in it and thus the pitch of note which it emits may be varied. The plate-spring C is pierced with an elongated hole C' rather larger than the string E and the string is

arranged to pass through this hole and to apply through the spring a light force tending to hold the armature away from the poles of its magnet. In addition to a tuning 5 pin at F for varying the tension in the string, a slideable bridge G is provided, held by the tension of the string, between the string and its sounding-board.

In use, the pitch of the string is tuned to 10 that of the impulses which it is desired to receive selectively; the position of the nodes and, if necessary, the final adjustment of the pitch, is obtained by moving the bridge into the required position. Current-impulses of 15 all sorts of periodicities imparted to the electro-magnet make the armature tend to vibrate in response. The mechanical interconnection with the string, however, prevents free response to these impulses unless 20 they are of the predetermined periodicity and the resiliency of the spring C tends to absorb the mutual impulses between the string and armature. When, however, an impulse is received whose periodicity corre- 25 sponds with the note to which the string has been tuned, the response is quite free since the string responds synchronously to the forces applied to it by the armature. In result, the string with its sounding-board emits 30 a clear loud sound of the note to which it has been tuned, so that the operator can listen to the signals received, for example as dots and dashes, without difficulty.

If it is desired to transmit the signals from 35 the apparatus just above described to some distance, or to magnify them for any purpose, the construction of Figs. 3 and 4 may be used. In this construction a microphone H is mounted with its diaphragm on the ar- 40 mature of the electro-magnet, and its body- portion supported from the magnet-core by a bridge-piece J.

It is to be understood that the microphone 45 may be mounted either upon the sounding- board, upon the electro-magnet armature as shown, or upon even the string itself. Of the three said positions for the microphone, the first will give the greatest purity of tone, and the second will give the greatest loud- 50 ness while the last will give a result, as compared with those of the other two, intermediate between these two. The microphone is connected in series with a telephone-receiver and battery in the known manner whereby 55 the audible signals may be finally received in the telephone.

Obviously either the string or the arma- 60 ture may be arranged to operate, when the amplitude of its vibrations becomes suffi- ciently great, through the aforesaid reso- 65 nance, any indicating or signaling device. As an example of such application, the de- vice shown in Fig. 5 may be cited. In this construction a commutator device bearing a resiliently controlled fly, such as is described

in my British Patent No. 110569 dated Octo- 70 ber 20th, 1916, may be employed as indi- cated at O. With this, nothing useful oc- curs until resonance arises between the string and the tongue B. At such times, 75 however, the spring C, which is elongated for the purpose of engaging with the toothed wheel P and slightly bent at its tip toward the wheel, causes the latter to rotate, and thus closes the circuit between two terminals 75 L which may be connected to any electrical circuit that may be convenient and so operate an indicator or recorder included in such circuit. The terminals to the windings of the electro-magnet A, are shown at K. 80

It is to be understood that other tunable resonators than a stretched string may be employed; for example a tunable reed may be used.

An important feature of the present in- 85 vention is a construction which provides both a tone-filtering function and an audi- ble result without necessitating the employ- ment of a microphone or telephone.

The use of the apparatus is not confined to 90 signaling as ordinarily understood but it may be employed to detect the occurrence of a vibration of a particular pitch or periodicity. When such vibration occurs, the reso- 95 nator announces its occurrence audibly.

What I claim as my invention and desire to secure by Letters Patent is:—

1. In a tone filter of the class described, in combination, a transmitting member, a string resonating member, and means con- 100 nnecting said transmitter and resonator comprising a spring secured to the transmitting member and having an aperture through which the string passes, said aperture being larger than the string.

2. In a tone filter of the class described in combination, a transmitting member includ- 110 ing an armature and electro-magnets, a string resonating member, and means con- necting said transmitter and resonator comprising a spring secured to one of said mem- bers and normally tending to hold the arma- ture away from the magnet.

3. In a tone filter of the class described, in combination, a transmitter including an 115 armature, a resonator, and a spring mounted on said armature and connecting said trans- mitter and resonator, substantially as de- scribed.

4. In a tone filter of the class described, in combination, a transmitter, a resonator, 120 mechanical connecting means between said transmitter and resonator, and adjustable means for determining the position of the nodes of the resonator, for the purpose set 125 forth.

5. In a tone filter of the class described, in combination, a transmitting member, a 130 resonating member, connecting means be- tween said transmitting and resonating mem-

bers, and a microphone mounted on the transmitting member, for the purpose set forth.

6. In a tone filter of the class described, 5 in combination, a transmitter including an armature, string resonator and resilient means connecting said transmitter and reso-

nator comprising a spring mounted on said armature and having an aperture therein through which the string resonator extends, 10 for the purpose set forth.

In testimony whereof I affix my signature.

SERGE OULIANINE.
